[57] CLAIM

The ornamental design for a combination accessory tray and book support for bathtubs or the like, as shown and described.

DESCRIPTION

FIG. 1 is a perspective view of a combination accessory tray and book support for bathtubs or the like, viewed from a position above and to the front, showing my new design;

FIG. 2 is a perspective view of the same, viewed from a position below and to the front thereof;

FIG. 3 is a top plan view thereof;

FIG. 4 is a front elevation view thereof; and

FIG. 5 is a vertical section view viewed from the line 5—5 of FIG. 4.
